HERBERT ERNEST DAKIN, OF LONDON, ENGLAND, ASSIGNOR TO BARNETT SAMUEL AND SONS, LIMITED, OF LONDON, ENGLAND, A CORPORATION OF GREAT BRITAIN.

TALKING-MACHINE STOP.

1,409,085.

Specification of Letters Patent.

Patented Mar. 7, 1922.

Application filed October 31, 1921. Serial No. 511,764.

To all whom it may concern:

Be it known that I, HERBERT ERNEST DAKIN, a subject of the King of Great Britain and Ireland, residing at 31-33 High Holborn, London, W. C., England, have invented certain new and useful improvements in Talking-Machine Stops, (for which I have filed an application in England, April 24, 1920,) of which the following is a specification.

This invention relates to devices for automatically stopping a talking machine when the stylus reaches the end of a record, and particularly to that type of apparatus in which the stopping device, such as a brake acting on the turn table, is held inoperative by the weight of the tone arm and is released when the tone arm reaches a predetermined position.

The object of the present invention is to facilitate the setting or adjustment of the automatic stopping device prior to each operation so that the turn table will be arrested immediately the record has been played, irrespective of the length of the record.

According to the invention a spring actuated brake is adapted to be held inoperative by the weight of the tone-arm during the playing of a record, the tone-arm or a member connected thereto riding over and depressing a plate which is adjustably mounted on the brake mechanism, so that the effective length of the plate, determining the period during which it is held depressed with the brake inoperative may be varied to suit the length of record to be played.

Moreover the plate is preferably adapted to be so engaged with the tone-arm or the aforesaid member connected thereto, at the end of the travel of the same over the plate, that the adjustment of the plate relatively to the brake mechanism can be effected by a simple manual movement of the tone-arm into the position corresponding to that in which the stylus is at the end of the record, or other point at which the brake is to act. The tone-arm is then disengaged from the plate (either by depressing the plate or by raising the tone-arm, according to the type of tone arm employed) and is moved back

to bring the stylus at the starting point on the record.

In the accompanying drawings:

Fig. 1 is a perspective view of one form of automatic talking machine stopping device shown in position on the motor board of a talking machine, a portion of the tone-arm being indicated in dotted lines.

Figs. 2 and 3 are respectively a side elevation and plan of the stopping device detached, the brake lever being of a slightly modified form.

Figs. 4 and 5 are perspective views of other forms of the stopping device.

Fig. 6 is a perspective view of a further form especially designed for use with a tone-arm of the type which can only swivel in one plane.

Figs. 7 and 8 are respectively a perspective view and a rear elevation of a still further form adapted to be mounted on the hinge of the lid of a talking machine casting.

In the form of the stopping device shown in Figs. 1 to 3, a brake lever 1, provided with a brake pad 2, for engagement with the edge of the turn-table 3, is pivoted at 4 in a bracket 5, secured to the motor board 6 of the talking machine. A spring 7 tends to maintain the lever with the pad 2 in contact with the turn table 3. The rear end 8 of the brake lever 1 is provided with a plate 9, which during the playing of a record, is depressed by the weight of the tone-arm, 85 acting through a member 10 which rides over the plate. While the plate 9 is depressed the brake pad 2 is withheld from the turn table 3. When the member 10 rides off the plate 9, for instance when it enters a slot 11, the brake lever 1 is moved by the spring 7 and forces the brake pad 2 into contact with the edge of the turn-table and arrests the table. The length of the plate between the slot 11 and the starting position 95 of the member 10 thereon, determines the time during which the turn-table is free to rotate, and consequently the position of the tone-arm, and that of the stylus on the record, when the turn table is arrested by the 100 brake.

In order to allow this effective length of the plate 9 to be varied to suit

records of different length, the plate 9 is adjustably mounted on the end 8 of the brake lever 1. For example the plate 9 has a slot 12. Two lugs 13 stamped out of the end 8 pass through the slot 12 and also through a spring washer 14' and are then bent over, so as to hold the washer 14' in position. The end 8 and plate 9 are curved approximately to a radius from the vertical axis 10 about which the tone-arm swings. The plate 9 is thus slidably and frictionally held on the end 8 so that it can be readily adjusted thereon. It may be manually adjusted.

15 It is preferred however to effect the adjustment by a manual movement of the tone-arm, and for this purpose the tone-arm, through the medium of the member 10 is adapted to engage with the plate 9, for example the plate is provided with two up-standing stops 14, and 15. If the member 10 be on top of the plate 9 as shown in Fig. 1, and the tone-arm be then moved by hand outwardly the member 10 will engage with 25 the stop 15 and the plate 9 will be slid outwardly to its full extent and then arrest the tone-arm. If now it be desired to set or adjust the automatic stopping device so that it shall apply the brake and stop the 30 turn-table immediately a particular record has been completely played, the tone-arm is moved inwardly until the member 10 engages the stop 14. The brake lever 1 raises the plate 9, so that the member 10 is 35 within the slot 11. The tone-arm is then moved either inwardly or outwardly to bring the stylus to the exact point at the end of the record where the playing is to cease. This movement, owing to the engagement 40 between the member 10 of the tone-arm and the plate 9, effects an automatic adjustment of the plate 9 on the end 8 of the brake lever 1, in other words it determines the effective length of the portion of, or track on the 45 plate 9 over which the member 10 will ride, during the subsequent playing of the record. When this adjustment has been effected, the tone-arm is disengaged from the plate 9 and moved outwardly to bring the stylus to the 50 starting point on the record. The disengagement of the member 10 and the plate 9 may be effected by merely raising the tone-arm or by manually depressing the plate 9, according as the tone-arm is of the type 55 which is capable of universal movement or the type which can only be moved in one plane, both types being commonly adopted in practice. When the stylus has been so placed at the starting point on the record, 60 the weight of the tone-arm will hold the brake lever 1 inoperative so that the turn-table is free to rotate. The stylus then travels across the record as usual until the member 10 rides off the plate 9, and enters 65 the slot 11 which occurs when the stylus

reaches the predetermined point, for instance the end of the record, and the brake lever 1 is moved by its spring 7 and applies the brake pad 2, to, and arrests the turn-table 3.

70 In the form of the automatic stopping device shown in Fig. 4 the brake pad 2 is intended to act against the under surface of the turn-table. The brake lever 1 is in the form of a plate and is adapted to be secured by a staple 16 to the motor board, a spring plate 17, secured to the brake lever bearing against the motor board and forcing the brake lever upwards. The leather or other pad 2 is adapted to be slid along a slot 80 19 in the lever 1 to allow it to be adjusted relatively to the turn-table. The brake lever 1 has a finger piece 18 by which it can be depressed. Its end 8 is adjustably fitted with a plate 9 as in the form before described, 85 similar reference numerals indicating corresponding parts.

90 The form shown in Fig. 5 is similar to that shown in Fig. 4, but the member 10 on the tone-arm is arranged to ride on the flat side of the plate instead of along an edge. Moreover the end 8 of the brake lever 1 is bent twice at right angles so that the end 8 and the plate 9 may overhang the record and turn-table. This arrangement is desirable when extra large records are used and 95 extend in close proximity to the support of the tone-arm.

99 The form shown in Fig. 6 is similar to that shown in Figs. 1 to 3. Two screws 20 and washers are used to secure the plate 9 slidably and frictionally to the end 8 of the brake lever 1. The lever 1 is also provided with a finger piece 18 by which it can be depressed.

105 In the form shown in Figs. 7 and 8 the brake lever 1 provided with a pad 2 for engagement with the underside of the turn-table is pivotally mounted on the pin 22 of the hinge 23 of the lid of the talking machine cabinet. Another lever 24 is also pivoted on the hinge pin 22. The plate 9 is adjustably mounted on the end 8 of the lever 24 similarly to the plate 9 of the previous examples.

110 A spring 25 tends to move the brake lever 1 to bring its pad 2 into contact with the underside of the turn-table. Another spring 26 tends to distend the two levers 1 and 24 relatively to one another. When the tone-arm depresses the plate 9 and therefore the lever 24 it tensions the spring 26 which is sufficiently strong to overcome the lighter spring 25, so that the brake lever 1 is depressed and withdraws the pad 2 from the turn-table. When the member 10 rides off the plate 9 into the slot 11 the lever 24 rises, slackens the spring 26 so that the spring 25 applies the brake pad 2 to the 120 turn-table. A lug 27 Fig. 8 on the brake 125 130

lever 1, near the hinge pin 23, prevents undue movement of the lever 22 when the tone-arm, which may be of the type which is pivoted universally is raised and replaced 5 to its starting point.

What I claim as my invention and desire to secure by Letters Patent in the United States of America is:—

1. A device for automatically stopping a talking machine comprising a swinging and spring actuated brake lever having a plate, a member connected to the tone-arm of the talking machine adapted to ride over said plate during the playing of a record to 10
15 press the same and to hold the brake inoperative, said plate being adjustable relatively to said brake to permit of the effective length of the plate ridden over by the aforesaid member to be varied to suit the length 20 of record to be played and provided with means to permit the brake lever to move into operative position, and means for engaging said member and plate whereby said plate may be adjusted relatively to said brake, by 25
30 manual movements of the tone arm, substantially as and for the purpose hereinbefore set forth.
2. A device for automatically stopping a talking machine, comprising a pivoted and spring actuated brake lever, a plate carried by said lever, adapted to be depressed by a member on the tone-arm of the talking machine, as the tone-arm swings about its vertical pivotal axis to hold said brake lever 35 in an inoperative position, said plate having a slot for the reception of said member when it reaches said slot to allow said plate to rise and permit said brake lever to move into an operative position, said plate being 40
45 adjustably mounted on said brake lever for the purpose of permitting of adjustment of the position of the slot in said plate relatively to the starting position of the said tone-arm member on said plate and provided with stops to permit the plate to be moved relatively to the brake by the manual move-

ment of the tone arm, substantially as and for the purpose hereinbefore set forth.

3. A device for stopping talking machines, comprising a swinging and spring pressed 50 brake lever having an angular end, a plate slidably secured to the angular end of the brake lever and having an open slot in its upper edge, and a member carried by the tone arm adapted to ride over the plate 55 to hold the brake in inoperative position during the playing of the record and to enter the slot of said plate to permit the brake lever to move into operative position.

4. A device for stopping talking machines, 60 comprising a pivoted and spring-pressed brake lever having an angular end, a plate slidably secured to the angular end of the brake lever and provided with stops at its ends and with an open slot adjacent to one 65 stop, and a member carried by the tone arm and adapted to ride upon said plate.

5. In a device for stopping a talking machine, a pivoted and spring pressed brake lever having an angular end, and a plate 70 slidably and frictionally mounted on the angular end of the brake lever, said plate being adapted to be ridden over by a member of the tone arm and provided with stops on its upper edge and an open slot adjacent 75 one stop.

6. In a device for stopping a talking machine, a pivoted and spring pressed brake lever having an angular end provided with lugs projecting therefrom, a longitudinally 80 slotted plate in which the lugs of the brake lever project, and means for securing the said lugs in the slot of the plate so that the plate will be frictionally held, said plate being adapted to be ridden over by a member 85 on the tone arm and provided with stops at its ends and an open slot adjacent one stop.

In testimony whereof I have affixed my signature.

HERBERT ERNEST DAKIN.
